US00D888094S

(12) **United States Design Patent** (10) **Patent No.:** **US D888,094 S**
(45) **Date of Patent:** **** Jun. 23, 2020**

(54) **DISPLAY PANEL OR PORTION THEREOF
WITH GRAPHICAL USER INTERFACE**

(71) Applicant: **Butterfly Network, Inc.**, Guilford, CT (US)

(72) Inventor: **David Elgena**, Brooklyn, NY (US)

(73) Assignee: **Butterfly Network, Inc.**, Guilford, CT (US)

(**) Term: **15 Years**

(21) Appl. No.: **29/661,978**

(22) Filed: **Aug. 31, 2018**

(51) LOC (12) Cl. **14-04**

(52) U.S. Cl.

USPC **D14/489**; D14/487

(57) **CLAIM**

The ornamental design for a display panel or portion thereof with graphical user interface, as shown and described.

DESCRIPTION

FIG. 1 is a front view of a display panel or portion thereof with graphical user interface showing our new design; and, FIG. 2 is a front view thereof shown with environmental matter.

The dot-dash broken lines illustrate a display panel or portion thereof and form no part of the claimed design. The dash-dot broken lines on the display panel represent portions of the graphical user interface that form no part of the claimed design. The broken lines in FIG. 2 showing a display device illustrate environmental matter that forms no part of the claimed design.

1 Claim, 2 Drawing Sheets
